CLAIM

The ornamental design for a ski boat awning, as shown and described.

DESCRIPTION

FIG. 1 is a perspective view of a ski boat awning showing my new design, the broken lines are for illustrative purposes only and form no part of the claimed design; FIG. 2 is a front elevational view thereof, a portion of the upright support member is shown broken away for convenience of illustration;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof, the support member is being omitted for clarity of illustration;

FIG. 8 is a perspective view thereof;

FIG. 9 is a top plan view of a second embodiment of the ski boat awning; and,

FIG. 10 is a top plan view of a third embodiment of the ski boat awning.

The sole difference among the first, second and third embodiments being the configuration of the top panel of the awning. The undisclosed bottom, sides, front and rear views of the second and third embodiments being the same as the first embodiment.
